COAL WASHING MACHINE

George Norton, Handsworth, England

Application December 22, 1931, Serial No. 582,593,
and in Great Britain December 31, 1930

3 Claims. (Cl. 209—496)

This invention relates to coal washing machines of the type in which the coal during the process of washing is passed over a bed of perforated plates or bars and is subjected to the pulsating action of water acting through the bed. In this type of machine the efficiency of the washing depends on maintaining, in conjunction with suitable water currents, a correct depth of stone or shale underneath the coal. Since this bed is continually being added to by the debris—chiefly shale—removed from the coal a means of drawing off the surplus shale is of necessity provided. For controlling the depth of the shale bed various means have been adopted, the most usual method being to allow the surplus shale to work its way through a pair of adjustable gate openings, one at each end of the washing bed, it being the duty of the attendant to examine the bed periodically—usually by prodding to ascertain its depth and density—and adjust the hand gates so as to maintain the required conditions.

In addition to the system of hand control referred to above, various methods have been adopted for automatically regulating the egress of the shale by means of mechanically, electrically, and pneumatically controlled devices. The present invention relates to the mechanically operated rotary gate type of control gear.

The invention has for one of its objects to provide an improved form of control gear for a rotary gate in which the motion is only transmitted to the gear when a movement of the gate is required.

Another object of the invention is to provide a rotary gate operated by a pawl and ratchet gear so arranged that the operating pawl is always fully in mesh with the ratchet wheel but is only operated when a movement of the gate is required.

A further object of the invention is to combine the above ratchet and pawl gear with operating mechanism controlled by a float resting on the top of the shale bed.

A still further object of the invention is to provide a swing hand gate operating in conjunction with the controlled rotary gate to control the depth of shale passing to the rotary gate as hereinafter described.

To enable the invention to be fully understood it will now be described by reference to the accompanying drawings in which:

Fig. 1 is a sectional elevation of one end of a coal washing box having one form of the invention applied thereto, and

Fig. 2 is a sectional end elevation of a part of the box.

Referring to the drawings, the washing box 1 is of known construction and comprises perforated bed plates 2, suitably supported and upon which shale or stone 3 lies while coal 4 is shown as partially floating due to the upward current of water passing through the box. The water level is indicated at 5.

A float 6 resting on top of the shale bed 3 is connected by a rod 7 to one end of a float lever 8 secured to a fulcrum shaft 9 carried in a bracket 10 mounted on the top of the box. A balance weight 11 is provided on the other end of the lever 8 and the depth of shale lying under the float is shown on an indicator plate 12 by the pointed end of the lever 8. The rod 7 is guided by means such as the friction roller 13. The shale is discharged through an opening 14 and two gates are provided for regulating the discharge. One gate 15 is mounted on a rock shaft 16 adapted to be rocked by a hand lever 17, the shaft being mounted in the side plates 18. The function of the gate is to regulate the depth of shale passing to the main shale gate 19 which is a mechanically operated gate of the known rotary type. The gate 19 is carried on a spindle 20 mounted in the side plates 18 and a ratchet wheel 21 is secured upon the end of the spindle 20 outside the box. A lever 22 is loosely mounted on the end of the spindle 20 and carries a pawl 23 which engages with the teeth of the ratchet wheel 21. A retaining pawl 24 serving to prevent any backward motion of the wheel 21 is also provided. The free end of the lever 22 is connected by a link 25 to one arm 26 of a bell crank lever which is loosely mounted on a rock shaft 27 carried in bearings on the top of the box. A lever 28 is keyed to the shaft 27 and carries a hinged extension piece 29 while on the opposite end of the shaft a second lever 30 is secured. The arm 31 of the bell crank lever carries a rigid extension 32 shaped as shown adapted to engage with the extension piece 29. The engaging faces of the pieces 29, 32 are fitted with hardened steel "hit and miss" plates 33, 34. The shaft 27 is rocked continuously by any suitable mechanism here shown as an eccentric rod 35 driven from any suitable source usually the overhead shaft of the washer box (not shown).

A lever 36 is secured to the end of the shaft 9, beyond the weight 11 and a link 37 adjustable in height by means of the handwheel 38 connects the end of the lever 36 to the hinged extension piece 29. The action of the above

described automatic control mechanism is as follows:—

It will be understood that the washing box is supplied with water and with pulsating means 5 and with a supply of coal to be washed in any usual manner.

The depth of the shale bed 3 is first adjusted to give the desired results in washing and the hand wheel 38 is set so as to lift the plate 33 10 just clear of its companion plate 34. The "hit and miss" plates 33 and 34 are now in the "miss" position and although the plate 33 is swinging backwards and forwards due to the action of the eccentric rod 35 acting through

15 the shaft 27, the loosely mounted bell crank lever 26, 31 and consequently the link 25, the lever 22 and the rotary gate 19 are at rest, the lever 22 resting on a fixed stop 38', and no shale is being ejected from the washer box.

20 During the operation of coal washing, shale is being continually deposited on the bed and in consequence the float 6 is gradually forced upwards until it reaches a point when the rising of the front end of the float lever 8 and the 25 consequent lowering of the rear end of the lever 36 with its attached link 37 causes the "hit and miss" plates 34 and 33 to make contact. This being so the motion of the lever 28 is transmitted to the lever 26, 31 and a vertically 30 reciprocating motion is imparted to the link 25 which acting through the medium of the lever 22, the pawl 23 and the ratchet wheel 21 imparts a slow rotating motion to the gate 19 thereby 35 ejecting the surplus shale.

35 Conversely it follows that the ejected shale causes a lowering of the bed 1 and the consequent lowering of the float 6 lifts the hinged piece 29 until the catch plate 33 is again in the "miss" position and the rotary movement of the 40 gate ceases, a sequence of operations which continues indefinitely.

It will be found that under certain conditions light shales may, due to the pulsations of the 45 water, be carried over the rotary gate 19, even when the latter is stationary, and to prevent the possibility of this happening one or more hinged plates 40 may be suspended so as to be just clear of the periphery of the rotary gate.

Such plates will effectually prevent the 50 possibility of shale being washed over the gate but in the event of "tramp iron" coming with the shale and projecting beyond the periphery of the gate the plates 39 are pushed backwards, righting themselves after the passage of the 55 projecting pieces.

Another advantage accruing from the construction is that in the event of auto-control gear being out of commission from any cause, it is quite possible to carry on washing by hand 60 control. Such a contingency calls for a slight raising of the hand gate 15 and the swinging back of the plates 39. This can be accomplished by means of a lever shaft and links or by any other suitable means, the ejected shale then 65 passing over the then stationary gate 19.

In the general construction as described above it will be noted that the mechanism is so arranged that the lever 22 and the pawl 23 operating the rotary gate are only in motion when a 70 movement of the rotary gate is required. Such a construction ensures that the operation pawl 23 is always fully in mesh with the ratchet wheel 21 and provides for the positive engagement of

the teeth when motion is transmitted to the ratchet lever 22.

It is here remarked that should the input of unwashed coal to the machine be interrupted even for lengthy periods the then stationary gate 80 19 definitely prevents the egress of shale and the gradual slipping out of the bed, a not infrequent happening with a shale gate of the sliding type, becomes an impossibility.

It will be understood that while the invention has been described with reference to apparatus for washing coal it may be used for washing ores and minerals of other kinds and it is not intended to restrict its use solely to the washing of 85 coal.

I claim:—

1. In a coal and mineral washing machine and in combination, a washer box, a perforated bed for the material to be washed mounted in the box, means for admitting water to the box, a discharge opening for the shale or heavier material, a hand operated gate controlling the passage of the heavier material to the discharge opening, a rotary gate mounted on a spindle and arranged behind the hand operated gate, a ratchet wheel on said spindle, a lever on said spindle carrying a pawl engaging the ratchet wheel, a link connected to the lever and to one arm of a bell crank lever loosely mounted on a rock shaft, the other arm of the lever carrying a rigid trip plate, means for rocking the shaft, a lever secured upon the rock shaft and carrying a hinged trip plate, an adjustable link attached to the hinged trip plate and to one end of a pivoted float lever, a link carrying a float attached to the other end of the float lever and an indicator plate mounted adjacent to the end of the lever carrying the float for the purposes described. 100

2. In a coal and mineral washing machine 115 as claimed in claim 1 and in combination, a swinging gate mounted on a spindle for controlling the passage of the heavier material to the rotary gate, a hand lever on the spindle, and a swinging plate mounted on and depending from the spindle and clearing the periphery of the rotary gate for the purpose described. 120

3. In a coal and mineral washing machine of the type referred to and in combination, a washer box, a perforated bed for the material to be washed mounted in the box, means for admitting water to the box, a discharge opening for the shale or heavier material, a rotary gate controlling the discharge opening and having a spindle, ratchet and pawl mechanism for operating 125 the rotary gate, comprising a ratchet wheel on the gate spindle, a rod, a driving pawl on the rod engaging the ratchet wheel, a lever on the gate spindle linked to said rod, a bell crank lever connected to said rod, a rock shaft loosely supporting the bell crank lever, a rigid extension member on the other arm of said lever, means for rocking the rock shaft continuously, a second lever having a hinged extension member secured upon the rock shaft, and float operated means 130 adjustably attached to the hinged extension member whereby the two extension members form a trip mechanism which engages and operates the rotary gate automatically only when movement of the gate is required by alteration 135 in the position of the float. 140

GEORGE NORTON.
